UNITED STATES PATENT OFFICE

164,477

DECANTER BOTTLE

John Collins and Harold A. Bowman, New York,
N. Y., assignors to Schenley Industries, Inc.,
New York, N. Y., a corporation of Delaware

Application May 31, 1950, Serial No. 10,272

Term of patent 14 years

(Cl. D58—6.5)

To all whom it may concern:

Be it known that we, John Collins and Harold A. Bowman, both citizens of the United States of America, residing at city, county, and State of New York, have invented a new, original, and ornamental Design for a Decanter Bottle, of which the following is a specification, reference being had to the accompanying drawing, forming part thereof:

Figure 1 is a perspective view of a decanter bottle embodying our new design; and

Figure 2 is a similar view, taken from the reverse side thereof.

We claim:

The ornamental design for a decanter bottle, as shown.

JOHN COLLINS.
HAROLD A. BOWMAN.
